AEROSOL HARD SURFACE CLEANER
Lyle F. Elmquist, North St. Paul, Minn., assignor to
General Mills, Inc., a corporation of Delaware
No Drawing. Filed Sept. 16, 1963, Ser. No. 309,299
2 Claims. (Cl. 252—90)

The present invention relates to an aerosol cleaner which is especially designed for use on hard surfaces. More particularly, it relates to such a cleaner consisting of a propellant, a cleansing concentrate and a small amount of an amorphous silica.

Cleaning compositions for difficult to clean hard surfaces, such as ovens, are shown. Typically, such compositions are viscous liquids which are applied to the surface to be cleaned with a brush, for example. While such compositions are fairly effective cleaners, the procedure employed in using them involves a certain amount of mess and inconvenience.

More recently, aerosol compositions have come into widespread use. A variety of having cream compositions are available in aerosol packages and even food products, such as dessert toppings, can be purchased in aerosol containers. Cleaning compositions, particularly window cleaners, are also available in this form. The use of aerosols reduces the inconvenience connected with conventional preparation and/or application of the various described compositions.

However, merely because aerosol packaging and application have come into widespread use does not mean the automatic solution to problems faced in any particular field of endeavor. In this respect, the conventional viscous liquid oven cleaners could not be simply admixed with a propellant and applied from an aerosol container. The preparation of aerosol hard surface cleaners presents various problems. Thus said compositions must have high cleansing power and still not be corrosive to the container or the surface to be cleaned. Additionally, such cleaners are especially designed for the cleaning of ovens and the like where vertical as well as horizontal surfaces are encountered. Where vertical surfaces are to be cleaned, the cleansing concentrate should have little or no tendency to run off the surface.

It is an object of the present invention to provide a novel aerosol hard surface cleaner.

Another object of my invention is to provide such a cleaner which has high cleansing power, is non-corrosive, foams and, when applied to non-horizontal surfaces, does not run off.

Still another object of the invention is to provide a novel aerosol hard surface cleaner consisting of a propellant, a cleansing concentrate and a small amount of an amorphous silica.

These and other objects will become apparent from the following detailed description.

I have now discovered that a highly useful aerosol hard surface cleaner is obtained by including a small amount of an amorphous silica in a composition otherwise consisting of a cleansing concentrate and a propellant. It was found that the amorphous silica prevents run off of the cleansing concentrate from non-horizontal surfaces while other known flow retarders, such as methyl cellulose, slow the flow of the cleaner but do not prevent it.

The cleansing concentrate consists essentially of an amphoteric detergent and a solvent. Especially preferred

2

amphoteric detergents are selected from compounds of the general structural formulae:

5 and

where R is hydrogen or a lower alkyl group containing less than four carbon atoms, R' is a high molecular weight, straight or branched chained, hydrocarbon radical containing 8 to 22 carbon atoms and X is hydrogen, alkali metal, ammonium or an alkanol amine such as mono-, di- or triethanol amine. X is preferably hydrogen, sodium, potassium or ammonium. These compounds are readily available commercial compounds. All may be classified as substituted products of beta-amino propionate where the hydrocarbon radical, R', is derived from various high molecular weight acids and contains the same number of carbon atoms as the original acid. Common sources of these acids are rosin acids and the fatty acids such as those obtained from tall oil, soybean oil, coconut oil, cottonseed oil, linseed oil, soapstock, safflower oil, castor oil, tallow, lard, and other fats and oils. It will be appreciated that the acids obtained from each source are generally a complex mixture, which are, for all intents and purposes, relatively uniform in composition. Thus, R' is often defined according to the source of the original acids, i.e., "coco"—coconut oil, "tallow"—tallow, "rosin"—rosin acids, and so forth.

20 30 The solvent comprises water, a lower aliphatic alcohol (1—4 carbon atoms) and a liquid hydrocarbon. Representative alcohols are methanol, ethanol and isopropanol with the latter being preferred. A representative and preferred liquid hydrocarbon is odorless mineral spirits. 25 35 Keosene can be employed where there is no objection to the type of odor which the cleansing concentrate has. More volatile hydrocarbons can be employed where no fire hazard is present.

40 In addition to the amphoteric detergent and solvent, the cleansing concentrate may also contain small amounts of other materials such as auxiliary cleaners. A representative and preferred auxiliary cleanser is ammonium hydroxide. Sodium and potassium hydroxide can also be used but are less preferred because of their caustic nature. Thus they present some corrosion problems and could cause injury if the cleansing concentrate was accidentally sprayed in such a manner as to come in contact with the user's eyes. Minor amounts of other known detergents can also be included although generally the amphoteric detergent provides sufficient cleansing power. A small amount of glycerine can be included to prevent the drying out of the product when sprayed and left to work for a time before being wiped off.

45 50 55 The propellant may be selected from any of those commonly employed in aerosol compositions. Representative propellants are trifluoro trichloro ethane (Freon 113), dichloro difluoro methane (Freon 12), tetrafluoro dichloro ethane (Freon 114), pentafluoro monochloro ethane (Freon 115), octafluoropropane (Freon 218), cyclic octafluorobutane (Freon C-318), propane, isobutane, butane and the like. Mixtures of various propellants can also be used. The preferred propellants are the non-flammable Freons, isobutane or mixtures of propane and isobutane.

60 65 The amorphous silica is used in an amount sufficient to prevent run off of the cleansing concentrate upon appli-

cation thereof on non-horizontal surfaces. Such amounts will preferably be within the range of about 1 to 2% by weight based on the total weight of the ingredients in the aerosol container. The preferred amorphous silicas have a particle size range of .005 to about 0.1 micron. A particularly preferred amorphous silica is Cab-O-Sil which has a particle size range of .015-.020 micron. Cab-O-Sil has the following additional properties:

SiO ₂ content (moisture-free basis) --- percent	99
Surface area (BET-nitrogen adsorption method) sq. m./gram	175-200
Specific gravity	2.1-2.2
Color	White
Refractive index	1.55
Fe ₂ O ₃ --- percent	0.004
CaO, MgO	None
Acidity value (m.e. NaOH to pH 7)	0.04
Free moisture (105° C.) --- percent	1.75
Ignition loss (1000° C.) --- do	2.5
Bulk density (uncompressed grade) lbs./cu. ft	2.5-3.5
pH (10% aqueous dispersion)	4.5-6.0
Oil absorption (Gardner method) lbs. pigment	150/100

The propellant, cleansing concentrate and amorphous silica can be packaged in any of the available pressure-tight containers having a valve-controlled opening which regulates flow through a discharge conduit leading to the base of the container. One such container is described in United States Patent 1,892,750. The container can be charged by chilling the mixed ingredients to a temperature at or below the temperature at which the propellant is in the liquid phase, introducing the chilled ingredients into the container and then sealing same. Of course, the propellant can be introduced separately and then the container can be sealed, or the propellant may be introduced after sealing. This latter procedure is preferred when using the hydrocarbon or low boiling fluorinated hydrocarbon propellants. The pressure-tight aerosol containers and the methods of charging same are well known and form no part of this invention.

The ratios of the various ingredients in my aerosol package can vary over relatively wide limits. Thus the propellant is used in an amount sufficient to evacuate the contents of the aerosol container and the amorphous silica is used in an amount sufficient to prevent flow or run off of the cleansing concentrate when applied to non-horizontal surfaces with the remainder consisting of the cleansing concentrate. Taking into account the ingredients of the cleansing concentrate, the preferred ratios are as follows:

Ingredient—	Parts by weight
Propellant	4-30
Amorphous silica	1-2
Cleansing concentrate:	
Amphoteric detergent	2.5-20
Water	5-70
Lower aliphatic alcohol	5-20
Liquid hydrocarbon	2-20
Glycerin	0-10
Auxiliary cleansers	0-10

Especially preferred ratios are as follows:

Ingredient—	Parts by weight
Propellant	5-15
Amorphous silica	1-2
Cleansing concentrate:	
Amphoteric detergent	2.5-10
Water	50-70
Lower aliphatic alcohol	7.5-15
Liquid hydrocarbon	2.5-7.5
Glycerin	2.5-7.5
Auxiliary cleanser	.10-5

The following examples are furnished for the purpose of illustration only and are not to be construed as placing any limitation on the scope of the present invention.

Example 1

An aerosol container was charged with the following ingredients:

Ingredient:	Parts by weight
Propellant (mixture of propane and isobutane)	5
Cab-O-Sil	2
Sodium N-coco β -aminopropionate	5
Water	67
Isopropyl alcohol	10
Odorless mineral spirits	5
Glycerin	5
Ammonium hydroxide (30%)	1
	100

When applied as an oven cleaner, the product showed excellent cleaning action and produced a cleanser foam on the oven surfaces which did not run off to any noticeable extent.

Example II

Example I was repeated except that methyl cellulose was used in place of the amorphous silica, Cab-O-Sil. The resulting applied product again had excellent cleaning action but a substantial amount of the cleanser foam flowed off of the non-horizontal surfaces in a fairly short time period.

Examples III and IV

Example I was repeated except that amorphous silicas having average particle sizes of 3-5 microns (Santocel C) and 3.3 microns (Sylloid 244) were used in place of the Cab-O-Sil. The run off properties of the cleanser were again unsatisfactory as in Example II.

Example V

40 Example I is repeated using disodium N-tallow β -iminodipropionate in place of the sodium N-coco β -aminopropionate. Equally good results are obtained. The terms coco and tallow refer to the fact that the R groups of the said amphoteric detergents were derived from the fatty acids 45 obtained from coconut oil and tallow, respectively.

Examples VI-VIII

Example I is repeated using ethyl alcohol in place of isopropyl alcohol in Example VI and leaving out the glycerine and ammonium hydroxide in Examples VII and VIII, respectively. Equally good results are obtained with the product of Example VI. The product of Example VII is also excellent but has a tendency to dry out when not wiped off the surface being cleaned in a relatively short time after application. The product of Example VIII has a slightly reduced cleansing action but in other respects is equal to the product of Example I.

The aerosol hard surface cleaners of the present invention are useful as oven cleaners. Generally they can be used as cleaners for metal surfaces, glass, ceramics, other non-metallic inorganic surfaces and on hard and relatively durable organic surfaces such as paint, plastics, linoleum and the like. In addition to their excellent cleansing and non-flow properties, they are also substantially non-corrosive and in many instances actually function as corrosion inhibitors.

70 It is to be understood that the invention is not to be limited to the exact details of operation or the exact processes shown or described, as obvious modifications and equivalents will be apparent to those skilled in the art and the invention is to be limited only by the scope of the appended claims.

I claim:

- 1 claim.
1. A package consisting of a pressure-tight container
75 having a valve-controlled opening charged with an aero-

sol hard surface cleaner consisting of the following ingredients in parts by weight:

Volatile propellant	5-15	
Amorphous silica	1-2	
Amphoteric detergent	2.5-10	
Water	50-70	
Lower aliphatic alcohol	7.5-15	
Liquid hydrocarbon	2.5-7.5	
Glycerin	2.5-7.5	
Auxiliary cleanser	.10-5	10

wherein said amorphous silica has a particle size range of about 0.005 to about 0.1 micron, said amphoteric detergent is selected from the group consisting of

and $R'N(CR_2CR_2COO)_2X_2$ where R is selected from the group consisting of hydrogen and lower alkyl radicals containing less than four carbon atoms, R' is an aliphatic hydrocarbon radical containing 8 to 22 carbon atoms and X is selected from the group consisting of hydrogen, alkali metal, and ammonium.

2. A package consisting of a pressure-tight container having a valve-controlled opening charged with an aerosol surface cleaner consisting of the following ingredients in parts by weight:

Propellant consisting of a mixture of propane and isobutane	5
Amorphous silica	2

Sodium N-coco β -aminopropionate	5
Water	67
Isopropyl alcohol	10
Odorless mineral spirits	5
5 Glycerin	5
Ammonium hydroxide (30% aqueous solution)	1

wherein said amorphous silica has a particle size range of .015 to .020 micron.

UNITED STATES PATENT OFFICE
CERTIFICATE OF CORRECTION

Patent No. 3,354,088

November 21, 1967

Lyle F. Elmquist

It is hereby certified that error appears in the above numbered patent requiring correction and that the said Letters Patent should read as corrected below.

Column 1, line 13, for "shown" read -- known --; line 20, for "having" read -- shaving --; line 21, for "ahd" read -- and --; column 2, line 17, for "radiacl" read -- radical --; line 36, for "Keosene" read -- Kerosene --; line 66, for "concentrate" read -- concentrate --; column 5, line 7, for "Lower aliphatic alcohol" read -- Aliphatic monohydric alcohol of 1-4 carbon atoms --; line 22, after "metal," strike out "and"; same line 22, after "ammonium" insert --, monoethanol amine, diethanol amine, and triethanol amine, and said auxiliary cleanser is selected from the group consisting of ammonium hydroxide, sodium hydroxide and potassium hydroxide --; line 24, after "aerosol" insert -- hard --.

Signed and sealed this 17th day of December 1968.
